UNITED STATES PATENT OFFICE

JOHN J. REINHOLD, OF MARIETTA, PENNSYLVANIA

DESIGN FOR A PAPER WEIGHT

Application filed December 26, 1931. Serial No. 42,218. Term of patent 14 years.

To all whom it may concern:

Be it known that I, JOHN J. REINHOLD, a citizen of the United States, and a resident of Marietta, county of Lancaster, State of Pennsylvania, have invented a new, original, and ornamental Design for a Paper Weight, of which the following is a specification, reference being had to the accompanying drawings forming a part thereof.

Fig. 1 represents a plan of my new design; and Fig. 2 represents a side elevation of the same.

I claim:

The ornamental design for a paper weight substantially as shown.

JOHN J. REINHOLD.
